PATENTED AUG. 11, 1908.

A. J. DOOLEY.

MACHINE FOR TWISTING WIRE INTO LIGHTNING RODS.

APPLICATION FILED DEC. 23, 1905.

UNITED STATES PATENT OFFICE.

ANDREW JACKSON DOOLEY, OF TOPEKA, KANSAS.

MACHINE FOR TWISTING WIRE INTO LIGHTNING-RODS.

No. 895,440.

Specification of Letters Patent. Patented Aug. 11, 1908.

Application filed December 28, 1905. Serial No. 293,686.

To all whom it may concern:

Be it known that I, ANDREW JACKSON DOOLEY, a citizen of the United States, residing at Topeka, in the county of Shawnee 5 and State of Kansas, have invented new and useful Improvements in Machines for Twisting Wire into Lightning-Rods, of which the following is a specification.

The objects of the invention are: to improve generally upon machines for making up lightning rods and like devices in the form of wire cables from a number of wires or strands.

Although my invention is designed primarily to make lightning rods, it will be quite plain that its utility is not confined to lightning rods but that the product may be applied to other uses, this patent having to do with the machine itself and not with the product.

Further objects are, to provide a simple and efficient braiding machine; to provide such a machine in which the number of strands, the number of wires, the tensions, the battening, etc., may be varied by simple operations; and to provide the mechanisms and details hereinafter set forth and claimed.

The invention consists of the parts, improvements, and combinations hereinafter described and claimed.

In the drawings accompanying and forming part of this specification and in the description thereof, I have shown the invention in its preferred form, and have shown the best mode of applying the principles thereof; but it is to be understood that the invention itself is not confined to these drawings and the description of the drawings, that it may be applied to other uses, that parts and combinations as separately claimed may be used with or without other devices of like general nature, and that I contemplate changes in form, proportions, material, the transposition of parts, and the substitution of equivalent members without departing from the spirit of the invention.

Figure 1 is a central section of the spool and immediately adjacent parts. Fig. 2 is a top plan view of the twisting apparatus, the frame being supposed to be in horizontal position, though it is understood that in operation the entire twisting frame rotates. Fig. 3 is a side view. Figs. 4, 5 and 6 are details in section, through the lines 13'-13', 55 14'-14', and 15'-15', respectively, of Fig. 2. Like reference numerals indicate like or

corresponding parts throughout the several views.

The twisting apparatus may rest on cross-beams, or bearings, 80', 80", which provide suitable supports for the shafts on which the twister rotates. The shaft 81 is hollow and through it the several strands pass from the braiding apparatus into the twister. The other shaft 82 may be solid. Both are secured to their supports and do not rotate. The twister frame 83 is made up principally of the two pieces of bar iron 83', 83", of proper size and strength. At one end they are secured to the block 84 which is mounted 70 rotatably on the hollow shaft 81; and at the other end they are secured to the inside face of the drive sprocket 85.

Extending from side to side of the frame and suitably mounted therein is the spindle 75 or shaft comprising the two parts 86 and 87, the part 87 being pinned or keyed to the hub 88, to the flange of which is secured the sprocket 89. The inner end of the part 86, which is the removable shaft, is threaded as 80 at 90 and adapted to be screwed into the hub 88, as clearly indicated in Fig. 1. Another flanged hub 91 fits onto the removable shaft 86. 94 is any suitable spool on which the product of the machine, the finished braided 85 and twisted lightning rod in the case immediately in view is wound; and the purpose of the arrangement of the shaft, etc., is to provide a simple arrangement for putting in an empty spool and removing the filled one, so 90 that the cable need not be again unwound from the twisting machine onto another spool for the market. To place the spool in the machine, the shaft 86 is removed, the spool held in proper position, and the shaft 95 86 is then inserted and screwed up, by means of a pin inserted through the hole 93. The flange 91 is then pressed up and the wedge 92 driven into slot 92'; which firmly secures the spool. Obviously the spool may be readily 100 removed by knocking out the wedge 92 and unscrewing the removable shaft 86. Another shaft 95 is also extended between the frame and is provided with a small sprocket 96 and a bevel gear 97 which meshes with a 105 small bevel gear 98 secured onto the stub shaft 82. Now, the shaft 82 and gear 98 being stationary, as the twister frame is rotated by means of the drive sprocket 85, the shaft 95 is rotated by reason of the gear 97 engaging with gear 98 in revolving thereabout; and rotation is thereby communicated to the

spool 94 through the sprockets 96 and 89 and a sprocket chain connecting them but not here shown.

The cable coming from the inner end 81' of the hollow shaft 81, passes through the guide slot 99 which is made of two suitable rods extending from the threaded collar 100 which engages on the screw 103 and which has an arm 101 adapted to pass along the 10 channel in the channel iron 102 to hold the collar from turning. As the screw 103 is turned in one direction or the other, the collar is moved along its length with the effect of shifting the cable so as to be wound up 15 uniformly on the spool. To turn the screw, and to alternately reverse the direction of rotation of the screw so as to send the collar back and forth the length of the spool, I have devised the mechanisms now to be described.

20 Keyed to the outer end of the screw is a ratchet whose teeth are faced both ways, so as to be adapted to be moved in either direction; to move it in one direction I provide the upper rack 105, and to move it in the other 25 direction I provide the lower rack 106. These two racks are movably mounted in slots in the guides 107 and 108 and are secured together by a rod or bar 109, to which is pivoted one end of a pitman 110 the other end of 30 which engages a wrist pin 111 on a disk 112 secured to a pinion 113 on a stub-shaft 114. The pinion meshes with a larger gear 115 keyed onto the shaft 87. The edge of each rack engaging the ratchet is divided into a 35 number of teeth adapted to one-way engagement with the ratchet so as to turn it only in one direction as it is reciprocated, as shown at 116, 116. They are connected by a spring 117 and also by a bar 127, the spring tending 40 to draw them toward each other so as to engage the ratchet teeth. The spring 118, one end of which is connected to the bracket 119 normally holds the lower rack 106 in engagement with the ratchet, and the upper rack out 45 of engagement therewith. On the outer end of a shaft 120 suitably mounted in the frame, is a cam or segment 121 loosely mounted on the shaft. A spring 124 connects the guide or bracket 107 with the long pin 122 extending 50 out from said cam. A shorter pin 123 also extends out from said segment, and between these two pins is a third pin 125 radially extending from the shaft 120. On the shaft 120, between the frame bars, are the collars 121', 55 and 122', each being properly secured thereto by a set-screw, and each having an inclined-plane surface adapted to be engaged by a finger 124' extending from the screw collar 100, as the said screw collar is moved to and fro along said screw 103. These inclined surfaces are indicated by the numeral 123". Also suitably secured to the shaft 120 as by a set-screw, is an arm 129 forming one member of a toggle joint the other member 130 of 60 which extends loosely through the cross-

piece 83" of the frame, and is provided with a compression spring 131 tending to force said joint against either one of the stop pins 132 according to the direction in which the arm 129 is turned by the shaft 120. The end of the lower rack 106 may be provided with a piece 126 which is merely to prevent the segment 121 from engaging the teeth of the rack.

The rotation of the shaft 87 causes a somewhat rapid reciprocating motion of the two racks through the gear 115, pinion 113, disk 112, pitman 110; and this motion thus imparts to the screw a right-hand motion by reason of the rack 105 engaging the ratchet 104. The pressure of the rack against the ratchet is not enough to prevent the rack teeth from slipping back over the ratchet teeth in their backward motion, the friction of the parts being enough to prevent this backward motion. And thus as the twister 85 is operated the screw collar with its guiding slot for the cable will be brought to the right (viewed from the left-hand end of the drawings). With such motion, too, the arm 124' will come into engagement with the inclined-plane surface 123" of the collar 121', and will thereby turn the shaft 120 until the toggle 129—130 has passed its "dead-center", when the spring 131 will throw it the remainder of the way around until the arm 129 rests 90 against the other pin 132, and this brings the other collar 122' into position with the inclined-plane surface in the line of travel of said arm 124', whereby as the direction of rotation of the screw is reversed said arm will 95 engage said other inclined-plane and again shift the spring toggle-joint. These two collars 121' and 122' are located approximately in line with the ends of the spool so as to carry the cable, in winding, from one end to the other, and the parts may obviously be adjusted so that the cable is wound closely and solidly upon the spool. The parts 120, 121, 122, 123, 124, and 125 are so adjusted 100 with relation to each other and with relation to the inclined planes and the spring toggle-joint, that the segment 121 does not leave the lower rack or the piece 126 until after the toggle-joint has passed its "dead-center"; nor are the spring 124, pin 122, and shaft 120 105 past their center-line until after the toggle-joint has passed its "dead-center". But said shaft 120 and pin 125 turn the segment against the tension of the spring 124 with the segment in engagement with the lower rack 120 or piece 126 up to the time that it carries the toggle-joint past its "dead-center," and then the segment and pin 122 are carried beyond their center line by the action of the spring 130 in turning the shaft after the shaft has 115 been turned to the "dead-center" line by the arm 124' and inclined plane. Whereupon the spring 118 draws up the lower rack into engagement with the ratchet and throws the upper rack out of engagement therewith, 120 125

with the result of reversing the direction of the screw rotation. By this means it will be seen that the inclined planes are adapted to move the toggle-joint just to and beyond the 5 "dead-center" line, and the further action of the spring in the toggle-joint moves the cam or segment into or out of full engagement with the rack; by which means I am able to overcome the necessity of a momentum for 10 carrying the parts beyond the dead-center line, and by which I provide a positively acting reversing mechanism.

Power may be transmitted to the twister and the braider from a common shaft having 15 sprockets connected by sprocket chains with the sprockets 85 and 43 respectively. As the twisted cable is wound up on the reel 94 the several strands and the individual wires are also drawn out from the several braiding 20 elements and off of the bobbins. The braiding is done in the several elements as heretofore described in detail through the operation of said shuttles and heddles, and the twisting is done between the outlet end 81' of the 25 hollow shaft 81 and the spool. The twisting apparatus revolves as a whole upon the stationary shafts 81 and 82. The twist may be regulated by increasing or decreasing the speed of the twister in relation to the speed 30 of the braider, and through the tension of the wires.

What I claim is:

1. In a wire-twisting machine the combination of a revoluble twister frame and a rotatable reel therein and means for actuating the same, a screw extending parallel with the axle of said spool, a cable-guide engaging

with said screw, driving means for the screw, and a toggle-joint device for positively reversing the direction of rotation of said 40 screw.

2. The combination of a reel, a screw, a cable-guide engaging with the screw, means for rotating the reel and means for rotating the screw, together with a spring toggle-joint for positively changing the direction of 45 rotation of the screw.

3. The combination of a frame, a spool, a screw, a threaded cable-guide engaging with the screw, means for rotating the spool, 50 means for rotating the screw in uniformity with the spool, and a spring-pressed toggle-joint for positively changing the direction of rotation of the screw.

4. The combination of a frame, a spool 55 mounted therein having an axle, a screw, a threaded cable - guide engaging with the screw, a ratchet secured to the screw, racks adapted to rotate the ratchet in opposite directions respectively, a pitman connection 60 between said axle and said racks, and two inclined planes and two spring-pressed toggle joints to automatically and alternately bring said racks into engagement with said ratchet to reverse the direction of motion of 65 said cable-guide.

In testimony whereof I have hereunto set my hand in the presence of subscribing witnesses.

ANDREW JACKSON DOOLEY.
